(57) **CLAIM**

The ornamental design for a lighting fixture, as shown and described.

DESCRIPTION

FIG. 1 is a perspective view of a lighting fixture;
FIG. 2 is a side, elevation view of the lighting fixture;
FIG. 3 is another side, elevation view of the lighting fixture;
FIG. 4 is a front, elevation view of the lighting fixture;
FIG. 5 is a rear, elevation view of the lighting fixture;
FIG. 6 is a top, plan view of the lighting fixture; and,
FIG. 7 is a bottom, plan view of the lighting fixture.
The broken lines in the drawings illustrate portions of the lighting fixture which forms no part of the claimed design.
